INTERNAL-COMBUSTION ENGINE

Johann Kremser, Hannover, Germany

Application July 31, 1953, Serial No. 371,522

Claims priority, application Germany December 22, 1952

4 Claims. (Cl. 123—55)

The present invention relates to a two-stroke cycle blower-scavenged internal combustion engine with its cylinders being arranged in form of a V, which differs from engines of this type known so far in that it is of a more suitable design and in that it is self-contained. The design of the drive for the governor, the oil pump, and the blower is somewhat difficult, as the numerous necessary gears and transmissions complicate the construction of the engine and necessitates larger dimensions, which is of particular disadvantage in engines for motor vehicles.

It is one object of the present invention to provide a two-stroke cycle blower-scavenged internal combustion engine, in which inside the banks of the V a cam shaft is journalled, which drives the oil pump as well as the governor, and which is driven by the crankshaft, if necessary by means of an intermediate gear; and the drive gear mounted to the cam shaft may at the same time drive the blower, whereby further gear elements are eliminated.

It is another object of the present invention to provide a two-stroke cycle blower-scavenged internal combustion engine, in which the room defined between the banks of the V forms the scavenging receiver, the cam shaft extending through said scavenging receiver, furthermore, the governor being arranged in the scavenging receiver, and the blower being mounted on top of said receiver. In accordance with the present invention, chambers or the like are provided in the scavenging receiver for the cam shaft and the pump drive and, respectively, for the governor with its drive. The scavenging receiver comprises a housing part which exactly fits between the banks of the V formed by the cylinders and is cast in one block with the chambers for the cam shaft, the pump drive and the governor. The tunnel for the cam shaft extending through said scavenging receiver is provided with bearing brackets at its ends.

Various embodiments in accordance with this invention are possible. With these and other objects in view which will become apparent in the following detailed description, the present invention will be clearly understood in connection with the accompanying drawing, in which:

Figure 1 is a front elevational view of a blower-scavenged two-stroke cycle internal combustion V-engine, partly in section; and

Fig. 2 is a longitudinal sectional view thereof.

The two cylinders 2 and 2' as herein shown are arranged in the form of a V and are mounted upon the engine block 1. A housing 3 is also mounted upon the engine block, but arranged between the cylinders 2 and 2' of the entire bank of cylinders and has formed therein a scavenging receiver 4. A blower 5 is mounted upon this housing 3.

Formed within this housing 3 is a tunnel 6 and a cham-

2

ber. Bearing brackets 8 supported within the opposite ends of the tunnel 6 have a cam shaft 9 journalled therein and one end of this cam shaft has a gear 10 keyed thereto whereas its opposite end is connected to a governor 11 for controlling the timing of the fuel injection by means of the meshing gears 12 and 13, said governor being disclosed in the copending application Serial No. 371,518, filed July 31, 1953. The governor 11 as well as the gears 12 and 13 are arranged within the chamber 7. The crankshaft 14 of the engine has keyed thereto a gear 15 and the latter is connected by an intermediate gear 16 to the gear 10 whereupon with rotation of the crankshaft 14 the cam shaft 9 will also be rotated. The shaft 17 of the blower 5 has keyed thereto a gear 18 which latter also meshes with the gear 10 of the cam shaft.

Furthermore, housing parts 19 are connected to the tunnel 6, said housing parts receiving the plungers 20 for the injection pump 21.

All main parts of the engine are fitted to the housing 3 which encloses the scavenging receiver. Before being fitted to the engine block said housing may be provided with the governor, the cam shaft and the pumps, so that it may be inserted between the banks of the V as a self-contained unit.

While I have disclosed one embodiment of the present invention, it is to be understood that this embodiment is given by example only and not in a limiting sense, the scope of the present invention being determined by the objects and the claims.

I claim:

1. A V-type two-cycle internal combustion engine comprising an engine block and a crankshaft supported in said engine block, ported engine cylinders mounted in V-formation upon said engine block and projecting therefrom, said cylinders defining a substantially V-shaped space therebetween, a housing disposed within the said space between the said cylinders and secured to the said engine block, and a scavenging receiver formed in said housing and communicating with said ported cylinder, chambers disposed in said housing coordinated to said cylinders, a fuel pump mounted in each of said chambers, a cam shaft supported within said housing for actuating each of said fuel pumps, a blower disposed on top of said housing and geared to said cam shaft and means for operatively connecting said cam shaft to said crankshaft of the engine.

2. The V-type two-cycle internal combustion engine as set forth in claim 1, which includes partition walls formed in the said housing for receiving said cam shaft.

3. The V-type two-cycle internal combustion engine as set forth in claim 1, in which the said housing containing said scavenging receiver with said cam shaft journalled therein, said fuel pumps, and said blower forms a removable single aggregate suitable for removably mounting on the said engine block between said cylinders.

4. The V-type two-cycle internal combustion engine as set forth in claim 1, which includes a tunnel-shaped chamber and means for supporting said cam shaft in said tunnel-shaped chamber.
